DUPLEX CURTAIN

Benjamin Holgate, Lowell, Mass., assignor to
 Boott Mills, Lowell, Mass., a corporation of
 Massachusetts

Application July 19, 1934, Serial No. 736,080

3 Claims. (Cl. 156—10)

My present invention relates generally to ornamental fabric curtains for window and like openings, and more particularly to curtains of that type which, in order to permit of the entry 5 of maximum light and air, and at the same time present a pleasing appearance, have been made in two hanging sections, each section presenting a net-like lengthwise panel adjacent to the other section and having the remaining portion 10 of a different relatively close woven material.

Up to the present time such curtain sections have been made up by stitching the lengthwise close woven and net panels together and it has been necessary not only to stitch gathered ruffles 15 around the edges of the sections but also along the said stitched adjoining edges of the panels in order to conceal the juncture thereof.

According to my invention, I form each of the curtain sections in a single piece having a loosely 20 woven net-like portion or panel adjacent to one side edge, and relatively close woven portions or panels at opposite sides of the loosely woven panel, one side panel being a relatively narrow edge band, so that the above stitching of panels 25 and concealment of the stitched edges is eliminated, with a consequent considerable reduction of the cost of manufacture, while retaining and, if anything, enhancing the pleasing appearance of the curtain as a whole.

30 The foregoing may be better understood and more thoroughly appreciated from the following detailed description of my invention, reference being had to the accompanying drawing, which forms a part of this specification, and in which,

35 Figure 1 is a front elevation illustrating my improved curtain in use, and

Figure 2 is a detail plan or face view of a portion of one of the sections.

40 Referring particularly to Figure 1, I have shown the two sections 10 and 11 of the curtain, each in one piece. The sections are of like form and constructed from a single oblong web of fabric. Each section includes a group of weft threads A and groups of warp threads B, C, and 45 D. The group A is common to the said other groups. The threads of group A are arranged throughout in equi-distant spaced relation and include intermediate stretches A', outer end stretches A'' and inner end stretches A'''. The 50 stretches A' are of greater length than the other of said stretches. The stretches A'' are of greater length than the stretches A'''. The warp threads of the group B are arranged throughout in substantially abutting relation. The warp 55 threads of the group D are arranged throughout in substantially abutting relation. The warp threads of the group C are arranged throughout in equi-distant spaced relation. The distance 60 between the warp threads of the group C is substantially the same as the distance between the

weft threads. The number of warp threads B is greater than the number of warp threads D. The number of warp threads C is greater than the number of warp threads B. The warp threads C coact with the intermediate stretches A' of 5 the threads A to form section 10 or 11 lengthwise and from end to end of the section with a loosely woven intermediate panel 12 of uniform width throughout and of lattice-like form to permit of entry of maximum light and air. The 10 threads of group B coact with the outer end stretches A' of the threads of group A to form the section 10 or 11 lengthwise and from end to end of the section with a closely woven outer side panel 14 of uniform width throughout and 15 of less width than panel 12. The panel 14 acts to conceal one side of the window frame. The threads of the group D coact with the inner end stretches A''' of the threads of group A to form the section 10 or 11 lengthwise and from end to 20 end of the section with a closely woven inner side panel 12 of uniform width throughout and of materially less width than panel 14. The panel 13 acts as a reinforcing means for the inner side of the section 10 or 11. 25

Owing to the above arrangement of the panels, the curtain in place at a window as in Figure 1 substantially conceals the window frame, by virtue of closely woven inner side panels 14, 30 and also the center sash bars, if there are such, by virtue of the inner closely woven outer side 13, leaving the loosely woven intermediate panels opposite to and extending across the major portions of the glass panes of the window sashes, or 35 the window opening if one or both sashes are open. The intermediate panels 12 are eccentrically disposed with respect to the side edges of the sections of the curtain.

In Figure 1 I have shown the loosely woven 40 intermediate panels 12 of the two curtains in a conventional cross weave, while in Figure 2 I have shown a somewhat more ornamental weave for the intermediate panels 12^a, and with reference to Figure 2, there is shown an outer side 45 group of warp threads 14' of the ordinary form, an inner side group of warp threads 14'' of the ordinary form and an intermediate group of warp threads 15 of the chain type. The group of weft threads common to the groups 14', 14'' and 15 50 is designated 16. The threads 16 include outer end stretches 16', intermediate stretches 16'' of greater length than the stretches 16' and inner end stretches 16''' of less length than the stretches 16'. The threads 14' and 14'' are 55 arranged relative to the stretches 16' and 16'' in the same manner as the threads B and D are arranged with respect to the stretches A'' and A'''. The threads 15 are arranged relative to each other in the same manner as the threads 60 C. The threads 15 are employed to separate

and bind off sets of the intermediate stretches 16" of the threads 16. The outer threads of the group 15 are spaced from the inner threads of the groups 14', 14''. The intermediate stretches 5 16" of each set are arranged in close proximity to each other from one outer thread to the other outer thread of the group 15. The threads 15 coact with the stretches 16" to provide the lattice-like intermediate panel 12a. The threads 10 14' coact with the stretches 16' to provide the outer side panel 14, and the threads 14'' coact with the stretches 16''' to form the inner side panel 13. However, this arrangement may 15 obviously be varied in other ways so long as the 16 loosely woven panel is of net-like nature in the sense that it readily distinguishes in appearance from the panels 13 and 14 and otherwise answers the foregoing requirements and purposes.

What I claim is:

- 20 1. As an improved article of manufacture, an ornamental window curtain in two similar hanging sections, each section comprising an oblong body including an outer side panel, an intermediate panel and an inner side panel, each of said 25 panels forming an integral lateral continuation from another and disposed lengthwise of and co-extensive with said body, said body being formed of an outer, an intermediate and an inner group of warp threads and a group of spaced weft threads common to the said other groups and with the weft threads being formed of outer end stretches, intermediate stretches and inner end stretches, the weft threads being permanently spaced from each other, the warp threads of the 30 outer group being arranged substantially in abutting relation throughout and coacting with said outer end stretches of the weft threads to provide the said outer side panel, the latter having a closely woven characteristic, the warp threads 35 of the inner group being arranged substantially in abutting relation throughout and coacting with the said inner end stretches of the weft threads to provide the said inner side panel, the latter having a closely woven characteristic, the said 40 warp threads of the intermediate group being permanently spaced from each other a substantial distance and coacting with the intermediate stretches of the weft threads to provide the said intermediate panel, the latter having a loosely woven characteristic to provide it throughout in the form of a lattice, said inner side panel being of a width materially less than that of said 45 outer side panel and constituting a reinforcing means for the inner side of the section, said intermediate panel being of a materially greater width than said outer side panel and of a form to provide for a maximum entry of air and light, and said outer side panel constituting a concealing means for the side of the window frame.
- 50 2. As an improved article of manufacture, an ornamental window curtain in two similar hanging sections, each section comprising an oblong body including an outer side panel, an intermediate panel and an inner side panel, each of said 55 panels forming an integral lateral continuation from another and disposed lengthwise of and co-extensive with said body, said body being formed of an outer, an intermediate and an inner group of warp threads and a group of spaced weft threads common to the said other groups, and with the weft threads being formed of outer end stretches, intermediate stretches and inner end stretches, the weft threads being permanently spaced from each other, the warp threads of the 60 outer group being arranged substantially in abutting relation throughout and coacting with said outer end stretches of the weft threads to provide the said outer side panel, the latter having a closely woven characteristic, the warp threads of the inner group being arranged substantially in abutting relation throughout and coacting with the said inner end stretches of the weft threads to provide the said inner side panel, the latter having a closely woven characteristic, the said 65 warp threads of the intermediate group being permanently spaced from each other a distance substantially equal to the distance between the weft threads and coacting with the intermediate stretches of the weft threads to provide the said 70 intermediate panel, the latter having a loosely woven characteristic to provide it throughout in the form of a lattice, the warp threads of the said intermediate group being of the chain type and connecting the intermediate stretches of the weft threads in spaced sets, each set consisting of a plurality of the said intermediate stretches arranged in close relation from a point in proximity to inner sides of the said other panels, said inner side panel being of a width materially less than that of said outer side panel and constituting a reinforcing means for the inner side of the section, said intermediate panel being of a materially greater width than said outer side panel and of a form to provide for a maximum entry of air and light, and said outer side panel constituting a concealing means for the side of a window frame.

ting relation throughout and coacting with said outer end stretches of the weft threads to provide the said outer side panel, the latter having a closely woven characteristic, the warp threads of the inner group being arranged substantially in abutting relation throughout and coacting with the said inner end stretches of the weft threads to provide the said inner side panel, the latter having a closely woven characteristic, the said warp threads of the intermediate group being permanently spaced from each other a distance substantially equal to the distance between the weft threads and coacting with the intermediate stretches of the weft threads to provide the said intermediate panel, the latter having a loosely woven characteristic to provide it throughout in the form of a lattice, said inner side panel being of a width materially less than that of said outer side panel and constituting a reinforcing means for the inner side of the section, said intermediate panel being of a materially greater width than said outer side panel and of a form to provide for maximum entry of air and light, and said outer side panel constituting a concealing means for the side of a window frame.

3. As an improved article of manufacture, an ornamental window curtain in two similar hanging sections, each section comprising an oblong body including an outer side panel, an intermediate panel and an inner side panel, each of said 30 panels forming an integral lateral continuation from another and disposed lengthwise of and co-extensive with said body, said body being formed of an outer, an intermediate and an inner group of warp threads and a group of spaced weft threads common to the said other groups, and with the weft threads being formed of outer end stretches, intermediate stretches and inner end stretches, the weft threads being permanently spaced from each other, the warp threads of the 35 outer group being arranged substantially in abutting relation throughout and coacting with said outer end stretches of the weft threads to provide the said outer side panel, the latter having a closely woven characteristic, the warp threads of the inner group being arranged substantially in abutting relation throughout and coacting with the said inner end stretches of the weft threads to provide the said inner side panel, the latter having a closely woven characteristic, the said 40 warp threads of the intermediate group being permanently spaced from each other a distance substantially equal to the distance between the weft threads and coacting with the intermediate stretches of the weft threads to provide the said 45 intermediate panel, the latter having a loosely woven characteristic to provide it throughout in the form of a lattice, the warp threads of the said intermediate group being of the chain type and connecting the intermediate stretches of the weft threads in spaced sets, each set consisting of a plurality of the said intermediate stretches arranged in close relation from a point in proximity to inner sides of the said other panels, said inner 50 side panel being of a width materially less than that of said outer side panel and constituting a reinforcing means for the inner side of the section, said intermediate panel being of a materially greater width than said outer side panel and of a form to provide for a maximum entry of air and light, and said outer side panel constituting a concealing means for the side of a window frame.
